UNITED STATES PATENT OFFICE.

JAMES HILL, OF CLEVELAND, OHIO.

FURNACE.

SPECIFICATION forming part of Letters Patent No. 325,175, dated August 25, 1885.

Application filed February 3, 1885. (No model.)

To all whom it may concern:

Be it known that I, JAMES HILL, of Cleveland, in the county of Cuyahoga and State of Ohio, have invented certain new and useful 5 Improvements in Furnaces for Roasting Ores; and I do hereby declare the following to be a full, clear, and exact description of the invention, such as will enable others skilled in the art to which it pertains to make and use the 10 same.

My invention relates to improvements in furnaces or ovens designed more especially for drying, annealing, and similar work, the object being to provide a traveling roof or cover 15 that may be elevated from the furnace and moved to one side by means of a tramway.

A further object is to provide a double furnace arranged so that the traveling cover when removed from one furnace will be in position 20 over the other furnace.

A further object is to provide compartments arranged in the mason-work in the body of the furnace for the reception of such articles as are to be dried, annealed, or otherwise treated.

With these objects in view my invention 25 consists in certain features of construction and in combination of parts, hereinafter described, and pointed out in the claims.

In the accompanying drawings, Figure 1 is a 30 side view in elevation of my improved furnaces. Fig. 2 is a plan view of the left-hand furnace with the cover removed. Fig. 3 is an elevation of the hearth and furnace with the cover removed. Fig. 4 is a section of the 35 furnace-roof.

A represents the outer walls or setting, as shown in Fig. 1, extending the length of two furnaces. The furnaces proper, B, are at the ends, and have doors B', for firing, and ash-pit doors B² and grates b arranged in the usual manner. In the center of the structure is a cross-wall, A', built up flush with the outer walls. Next to the furnace are the bridge-walls b'. The ovens proper, C, have double 40 floors of large tile c or fire-brick arranged to break joints and supported on piers D. The ends of the next adjacent tiers of flooring-tile are separated a short distance—about an inch, more or less—leaving a space, d, that, except 45 where the pieces extend under the corners of these tiles, is in open relation with the chamber E below the floor. Thin walls g of fire-

brick are built on either side of this opening, and the next adjacent walls are suitably connected by headers, as shown in Fig. 2, the 55 bridge-wall and the wall A' requiring only one wall, g, at the end opening. The opening d', next the wall A', is of considerable width, so that so much of the products of combustion as do not pass down through the smaller openings d may have an exit through this opening. The chamber E has a lateral flue, E', leading to a suitable chimney. (Not shown.) The walls g dividing the oven into compartments may, with the spaces d, piers D, and floors, be 65 arranged to make the compartments of any suitable size or of different sizes, according to the articles to be treated therein. By means of a divided draft passing through the spaces d and of the hot-air chamber E the floor and 70 walls g become heated, so that every part of the oven is effective in drying, annealing, or otherwise treating the articles placed therein.

F are heavy hollow irons, triangular in cross-section, as shown in Fig. 4, and firmly bolted together at the corners, the inner faces of which form springers for the four sides of the arched roof G. The fire-bricks that compose the roof extend below the irons F, as shown at g', Fig. 4, so that when the roof is in position over one 80 of the ovens the brick-work of the roof rests on the walls A and A'. Attached to the irons F are laterally-projecting spindles f, on which are mounted the wheels K, that travel on the track L, arranged on either side of the furnace. These tracks are supported by screw-rods H, that have flanges bolted to the track and fit into the respective bores of the caps I, that rest on the pilasters I'. The rods H have square threads, and the smooth bores of the 85 caps serve as guides for the rods H, that have nuts h for elevating the rods and track. When these rods and track are depressed, the roof G rests on the walls A and A', as aforesaid.

By turning the nuts h the track may be elevated until the roof is raised from the walls, after which the roof may be moved along by means of the track and wheels and brought in position over the other oven, of course leaving the oven from which the roof has been removed 90 open.

By this arrangement while one oven is being heated and operated the other oven is cooling off, and may be charged ready for fir-

ing up when the process in the heated oven shall have been completed. By this construction also is avoided the great expense usually incurred of iron boxes and other containers in which to place the articles to be treated in the ovens.

When it is practicable to do so, the earth is usually banked up around the furnace to near the bottom of the track, except at the furnace doors. This keeps the walls A from spreading, and prevents much radiation of heat from the walls.

What I claim is—

1. In a furnace or oven, the combination, with a traveling roof mounted on wheels, of a track and devices for elevating or depressing said track, whereby the roof may be moved bodily away from the furnace and returned and made to rest on the walls of the furnace, substantially as set forth.
2. The combination, with a double furnace,

a track located alongside of said double furnace, and devices for vertically adjusting said track, of a roof mounted on wheels and adapted to be moved from one section of the furnace to the other.

3. The combination, with a double furnace the floors of which are provided with openings, and a hot-air chamber located below said floors, of a track located alongside of said double furnace, devices for vertically adjusting the track, and a roof mounted on wheels and adapted to be moved from one section of the double furnace to the other, substantially as set forth.

In testimony whereof I sign this specification, in the presence of two witnesses, this 19th day of January, 1885.

JAMES HILL.
